(57) **CLAIM**

The ornamental design for a collapsible bathing cup with suction base, as shown and described.

DESCRIPTION

FIG. 1 is a front perspective view of a collapsible bathing cup with suction base, shown in an expanded configuration; FIG. 2 is a front elevational view of the collapsible bathing cup with suction base of FIG. 1, the rear elevational view being identical to the front elevational view;

FIG. 3 is a right-side elevational view of the collapsible bathing cup with suction base of FIG. 1, the left-side elevational view being identical to the right-side elevational view;

FIG. 4 is a top plan view of the collapsible bathing cup with suction base of FIG. 1;

FIG. 5 is a bottom plan view of the collapsible bathing cup with suction base of FIG. 1;

FIG. 6 is a bottom perspective view of the collapsible bathing cup with suction base of FIG. 1;

FIG. 7 is a front perspective view of a collapsible bathing cup with suction base, shown in a collapsed configuration; FIG. 8 is a front elevational view of the collapsible bathing cup with suction base of FIG. 7, the rear elevational view being identical to the front elevational view;

FIG. 9 is a right-side elevational view of the collapsible bathing cup with suction base of FIG. 7, the left-side elevational view being identical to the right-side elevational view;

FIG. 10 is a top plan view of the collapsible bathing cup with suction base of FIG. 7;

FIG. 11 is a bottom plan view of the collapsible bathing cup with suction base of FIG. 7; and,

FIG. 12 is a bottom perspective view of the collapsible bathing cup with suction base of FIG. 7.

(Continued)

The portions shown in broken line do not form part of the claimed design.
